UNITED STATES PATENT OFFICE.

MATHEW DOMNICK DUFFY AND BARTLEY PATRICK COSTELLO, OF CINCINNATI, OHIO.

MACHINE FOR GRINDING PIGMENTS.

1,154,004.

Specification of Letters Patent. Patented Sept. 21, 1915.

Application filed July 15, 1914. Serial No. 851,113.

To all whom it may concern:

Be it known that we, MATHEW DOMNICK DUFFY and BARTLEY PATRICK COSTELLO, citizens of the United States, residing at Cincinnati, in the county of Hamilton and State of Ohio, have invented certain new and useful Improvements in Machines for Grinding Pigments, of which the following is a specification.

10 This invention relates to improvements in machines for grinding pigments for paints and has for its object to provide a machine which, with one continuous operation will thoroughly grind pigments to a perfectly smooth paste.

Another object of the invention is to provide a paint grinding mill having a fixed semi-cylindrical grinding bed and a cylindrical grinder thereon.

20 Another object of the invention is to provide a grinding mill having a series of cylindrical grinders each having a scraper and means for simultaneously operating said scrapers.

25 Still another object of the invention is to provide a grinding machine having a series of grinding beds and means whereby said beds may be independently removed.

Still another object of the invention is to 30 provide a grinding machine having a plurality of water-cooled grinding beds.

With the above and other objects in view we have invented the device illustrated in the accompanying drawings in which—

35 Figure 1, is an elevational view of our mill. Fig. 2, is a longitudinal sectional view thereof. Fig. 3, is a detail elevational view of a grinding device separated from the mill proper, and Fig. 4, is a section taken 40 on line A—A of Fig. 3. Fig. 5, is a front elevational view of Fig. 1. Fig. 6, is an enlarged detail view of a scraper operating member.

45 Like reference characters indicate like parts throughout the several views in which—

1, indicates the frame of our mill in which are a series of boxes 2, 3 and 4, mounted in stepped relation. These boxes are of just 50 a size to receive the snugly fitting water receptacles 5, 6, and 7, having semi-cylindrical upper walls 8, 9 and 10, in which are seated the grinding beds 11, 12 and 13, which are made preferably of esophia stone, granite or steel or some other similar sub-

stance, and their upper faces are provided with several corrugations or grooves 14, which are adapted to check the passage of lumpy substances and cause them to be ground more finely between the upper surfaces 15, 16 and 17 and the cylinders 18, 19 and 20, which are fixedly mounted upon the mandrels 21, 22 and 23, by means of which they are rotated.

The members 5, 6 and 7, are mounted upon 60 brackets 24, 25 and 26, which terminate in screw collars 27, 28 and 29, which are screwed upon the upper ends of the vertical shafts 30, 31 and 32, which rest upon the bearings 33, 34 and 35, which carry bevel gears 36, 37 and 38, which mesh with the bevel gears 39, 40 and 41, on the horizontal shafts 42, 43 and 44, upon the outer ends of

which are hand wheels 45, 46 and 47, whereby said horizontal shafts may be operated 65 to in turn operate the vertical shafts operating in the collars 27, 28 and 29, whereby the members 5, 6 and 7, may be raised and lowered in order to regulate the grinding.

By rotating the shafts 30, 31 or 32, until 70 they become disconnected with the collars 27, 28 and 29, said shafts may be removed from the mill and the members 5, 6 or 7, removed in order that the beds 11, 12 or 13, 75 may be cleansed or renewed if worn out. The beds 11, 12 and 13, are each provided with end flanges 48 and 49, in order to prevent the material being ground from spilling from the sides of said beds.

Pivots mounted upon uprights 50 and 90 51, adjacent each of said cylinders 18, 19 and 20, are rods 52, 53 and 54, having right angular ends 58, 59 and 60, which carry scrapers 55, 56 and 57. Springs 61, 62 and 63, mounted between said members 95 58, 59 and 60, and the members 64, 65 and 66, which normally hold said scrapers firmly but resiliently against said cylinders 18, 19 and 20, whereby the paint adhering to the surface of said cylinders will be scraped 100 therefrom and into the troughs 67, 68 and 69, from which it will be fed to the next succeeding cylinder bed or to a suitable receptacle (not shown). A rod 70, connected by levers 71, 72 and 73, to the members 64, 105 65 and 66, is adapted to move said members simultaneously in one direction or another in order to move said scrapers into or out of contact with said cylinders 18, 19 and 20. The lever 73 is provided with a hand grip 110

74 and a pawl 75, operating the dog 76 adapted to engage with the teeth 77, whereby said rod 70, and its scrapers, may be held in desired position.

5 The mandrels 21, 22 and 23, are provided with gears 78, 79 and 80, connected by pinions 81, and 82, the gear 78 being driven by a transmission gear 83, which is driven by a gear 84, and a driving shaft 85, whereby all 10 of said cylinders 18, 19 and 20, are simultaneously operated. The material to be ground is fed from the hopper 86 to the chute 87, and thence to the first bed 11.

A pigment and oils are mixed in the hopper 86 and fed from there to the bed 11 where it is ground between said bed and the cylinder 18, to which the material will adhere and from which it is scraped into the chute 67, and fed to the bed 12, where it 15 goes through a second grinding and it is fed to the bed 13, where it receives its final grinding. Each succeeding cylinder is preferably a little closer to its respective bed than the preceding where the machine is in 20 operation, said beds being adjusted to suit the particular pigment or material being ground. After leaving the bed 13 and cylinder 20, the material is in a thoroughly 25 ground mass and is in proper condition for 30 use.

Having now described our invention, that which we claim to be new and desire to procure by Letters Patent is:—

1. A pigment grinder consisting of a series of horizontally disposed cylindrical grinders having smooth surfaces and semi-cylindrical removable beds, and water cooled supports for said beds.

2. A pigment grinder consisting of a series of horizontally disposed cylindrical grinders having smooth surfaces and semi-cylindrical removable beds, and water cooled supports for said beds, said supports being vertically adjustable.

45 3. A pigment grinder consisting of a series of horizontally disposed cylindrical grinders having smooth surfaces and semi-cylindrical removable beds, water cooled supports for said beds, said supports being 50 vertically adjustable, and vertical shafts upon which said supports are mounted.

55 4. A pigment grinder consisting of a series of horizontally disposed cylindrical grinders having smooth surfaces and semi-cylindrical removable beds, water cooled supports for said beds, said supports being vertically adjustable, and vertical shafts upon which said supports are mounted, said 60 shafts being the means whereby said supports are adjusted.

65 5. A pigment grinder consisting of a series of horizontally disposed cylindrical grinders having smooth surfaces and semi-cylindrical removable beds, water cooled supports for said beds, said supports being

vertically adjustable, and vertical shafts upon which said supports are mounted, said shafts being the means whereby said supports are adjusted, and said cylinders being arranged in stepped relation.

70 6. A pigment grinder consisting of a series of horizontally disposed cylindrical grinders having smooth surfaces and semi-cylindrical removable beds, water cooled supports for said beds, said supports being vertically adjustable, vertical shafts upon which said supports are mounted, said shafts being the means whereby said supports are adjusted, said cylinders being arranged in stepped relation, and means whereby said 75 pigment may be transferred from one grinder to another.

7. A pigment grinder consisting of a series of horizontally disposed cylindrical grinders having smooth surfaces and semi-cylindrical removable beds, water cooled supports for said beds, said supports being vertically adjustable, vertical shafts upon which said supports are mounted, said shafts being the means whereby said supports are adjusted, said cylinders being arranged in stepped relation, and means whereby said 80 pigment may be transferred from one grinder to another, said means consisting of troughs connecting said 85 grinders.

8. A pigment grinder consisting of a series of horizontally disposed cylindrical grinders having smooth surfaces and semi-cylindrical removable beds, water cooled supports for said beds, said supports being vertically adjustable, vertical shafts upon which said supports are mounted, said shafts being the means whereby said supports are adjusted, said cylinders being arranged in stepped relation, means whereby said 100 pigment may be transferred from one grinder to another, and said means consisting of troughs connecting said grinders, and 105 scrapers for said grinders.

110 9. A pigment grinder consisting of a series of horizontally disposed cylindrical grinders having smooth surfaces and semi-cylindrical removable beds, water cooled supports for said beds, said supports being vertically adjustable, vertical shafts upon which said supports are adjusted, said cylinders being arranged in stepped relation, means whereby said pigment may be transferred from one grinder to another, said means consisting of troughs connecting said 115 grinders, and scrapers for said grinders, and means for operating said scrapers.

120 10. A pigment grinder consisting of a series of horizontally disposed cylindrical grinders having smooth surfaces and semi-cylindrical removable beds, water cooled supports for said beds, said supports being vertically adjustable, vertical shafts upon which said supports are adjusted, said cylinders 125 125

ders being arranged in stepped relation, means whereby said pigment may be transferred from one grinder to another, said means consisting of troughs connecting said 5 grinders, scrapers for said grinders, and means for operating said scrapers simultaneously.

11. A pigment grinder consisting of a series of horizontally disposed cylindrical 10 grinders having smooth surfaces and semi-cylindrical removable beds, water cooled supports for said beds, said supports being vertically adjustable, vertical shafts upon which said supports are adjusted, said cylinders 15 being arranged in stepped relation, means whereby said pigment may be transferred, from one grinder to another, said means consisting of troughs connecting said grinders, scrapers for said grinders, and means for operating said scrapers simultaneously, means for operating said 20 shafts.

12. A pigment grinder consisting of a series of horizontally disposed cylindrical 25 grinders having smooth surfaces and semi-cylindrical removable beds, water cooled supports for said beds, said supports being vertically adjustable, vertical shafts upon which said supports are adjusted, said cylinders 30 being arranged in stepped relation, means whereby said pigment may be transferred from one grinder to another, said means consisting of troughs connecting said grinders, scrapers for said grinders, 35 means for operating said scrapers simultaneously, and means for operating said shafts, independently.

13. The described device consisting of cylinders arranged in stepped relation, beds 40 for said cylinders and vertically adjustable supports for said beds, said cylinders carrying gears and pinions connecting said gears, and troughs connecting said cylinders, and scrapers for each of said cylinders adapted 45 to scrape matter therefrom into said troughs.

14. The described device consisting of cylinders arranged in stepped relation, beds for said cylinders and vertically adjustable supports for said beds, said cylinders carrying gears and pinions connecting said gears, troughs connecting said cylinders, scrapers for each of said cylinders adapted to scrape matter therefrom into said troughs, and 55 means for simultaneously operating said scrapers.

15. The described device consisting of cylinders arranged in stepped relation, beds for said cylinders and vertically adjustable supports for said beds, said cylinders carrying gears and pinions connecting said gears, troughs connecting said cylinders, scrapers for each of said cylinders adapted 60 to scrape matter therefrom into said troughs, and means for simultaneously operating said 65 scrapers.

scrapers, each of said scrapers being spring controlled.

16. The described device consisting of cylinders arranged in stepped relation, beds for said cylinders and vertically adjustable 70 supports for said beds, said cylinders carrying gears and pinions connecting said gears, troughs connecting said cylinders, scrapers for each of said cylinders adapted to scrape matter therefrom into said troughs, 75 and means for simultaneously operating said scrapers, each of said scrapers being spring controlled, and said supports having water boxes for cooling said beds.

17. The described device consisting of cylinders arranged in stepped relation, beds for said cylinders and vertically adjustable supports for said beds, said cylinders carrying gears and pinions connecting said gears, troughs connecting said cylinders, scrapers for each of said cylinders adapted to scrape matter therefrom into said troughs, means for simultaneously operating said scrapers, each of said scrapers being spring controlled, said supports having water boxes 85 for cooling said beds, and a vertical shaft for supporting each of said boxes.

18. The described device consisting of cylinders arranged in stepped relation, beds for said cylinders and vertically adjustable supports for said beds, said cylinders carrying gears and pinions connecting said gears, troughs connecting said cylinders, scrapers for each of said cylinders adapted to scrape matter therefrom into said troughs, means 90 for simultaneously operating said scrapers, each of said scrapers being spring controlled, said supports having water boxes for cooling said beds, a vertical shaft for supporting each of said boxes, and screw connections between said shafts and boxes 95 whereby said vertical adjustment is obtained.

19. The described device consisting of cylinders arranged in stepped relation, beds for said cylinders and vertically adjustable supports for said beds, said cylinders carrying gears and pinions connecting said gears, troughs connecting said cylinders, scrapers for each of said cylinders adapted to scrape 100 matter therefrom into said troughs, means for simultaneously operating said scrapers, each of said scrapers being spring controlled, said supports having water boxes 105 for cooling said beds, a vertical shaft for supporting each of said boxes, screw connections between said shafts and boxes whereby said vertical adjustment is obtained, and independent means for operating each of said shafts.

20. The described device consisting of cylinders arranged in stepped relation, beds for said cylinders and vertically adjustable supports for said beds, said cylinders carrying gears and pinions connecting said gears, 110

troughs connecting said cylinders, scrapers for each of said cylinders adapted to scrape matter therefrom into said troughs, means for simultaneously operating said scrapers, 5 each of said scrapers being spring controlled, said supports having water boxes for cooling said beds, a vertical shaft for supporting each of said boxes, screw connections between said shafts and boxes 10 whereby said vertical adjustment is obtained, and independent means for operating each of said shafts, said rollers having smooth surfaces.

21. The described device consisting of cylinders arranged in stepped relation, beds for said cylinders and vertically adjustable supports for said beds, said cylinders carrying gears and pinions connecting said gears, troughs connecting said cylinders, scrapers 20 for each of said cylinders adapted to scrape matter therefrom into said troughs, means for simultaneously operating said scrapers, each of said scrapers being spring controlled, said supports having water boxes 25 for cooling said beds, a vertical shaft for supporting each of said boxes, screw connections between said shafts and boxes whereby said vertical adjustment is obtained, and independent means for operating each of said shafts, said rollers having smooth surfaces, and said beds having grooves.

22. The described grinding mill consisting of a series of cylindrical grinders ar-

ranged in stepped relation, said cylinders 35 being horizontally disposed, semi-cylindrical beds in which said cylinders rotate, said beds being adjustable, water boxes upon which said beds are mounted, said boxes having semi-cylindrical upper surfaces to 40 receive said beds, means for adjusting said beds, said means consisting of screw shafts, said shafts being vertically disposed, means for rotating said shafts, scrapers for each of said cylinders, means for simultaneously 45 rotating said cylinders, and boxes in which said beds are vertically movable, the upper surfaces of said beds being corrugated, and said water boxes being supported by said shafts.

23. A pigment grinder consisting of a series of horizontally disposed cylindrical grinders, a suitable bed for each cylindrical grinder, a scraper for each cylindrical grinder, and means connecting said scrapers 55 for simultaneously adjusting said scrapers relative to their respective cylindrical grinders, each scraper being provided with a spring whereby it is firmly but resiliently held against its cylinder.

In testimony whereof we affix our signatures in presence of two witnesses.
